UNITED STATES PATENT OFFICE

FRANK KUHN, OF DETROIT, MICHIGAN.

ELECTRICALLY-HEATED SAD-IRON.

No. 887,947.

Specification of Letters Patent.

Patented May 19, 1908.

Application filed September 14, 1907. Serial No. 392,915.

To all whom it may concern:

Be it known that I, FRANK KUHN, a citizen of the United States of America, residing at Detroit, in the county of Wayne and State 5 of Michigan, have invented certain new and useful Improvements in Electrically-Heated Sad-Irons, of which the following is a specification, reference being had therein to the accompanying drawings.

10 The invention relates to electrically-heated sad irons and consists in certain features of construction as hereinafter set forth.

In the drawings, Figures 1 and 2 is a perspective view of the parts composing the iron 15 detached; and Fig. 3 is a vertical longitudinal section through the iron.

My improved iron is composed of a flat base section A to which the heating elements are directly attached, and a superposed hood 20 section B having a handle C secured thereto.

The heating element is preferably formed of a plurality of units, each consisting of 25 laminated metallic conductors and alternate insulators, and these are preferably alternate sheets of metal foil and mica, as indicated by D and D', composing a unit E. These units are clamped directly to the base A, preferably by forming lugs F projecting upward from the base, which are machined or otherwise 30 fixed to form a good contact with the unit. As shown, three of the units are attached to the base, and are arranged with one unit extending centrally of the base from the forward pointed end thereof and two of 35 the units arranged upon opposite sides of and overlapping the rear portion of said forward unit. This produces a comparatively uniform distribution of heat, while the central and forward units extends the heating effect 40 to the point of the iron.

The three units are preferably connected in series, and preferably by metallic bridge pieces G extending between the adjacent or overlapping portions of the units. The terminal 45 connections are attached to the opposite side units and are arranged to pass upward and rearward through apertures in the hood section 3. For this purpose, each terminal preferably comprises a section H 50 formed of thin flexible and resilient material, having at its upper end a terminal post or pin I attached thereto, said post having a portion J which is surrounded by an insulating sleeve K and a threaded portion L having 55 a nut M thereon. The inner end of the post has a collar or shoulder N and the insulator

washers O and P, formed of mica or other suitable material, are also sleeved upon the post. The whole arrangement is such that the post I will pass through the apertures Q 60 in the rear end of the hood B, the insulator sleeves K fitting in said apertures and the washers O and P bearing against the hood on the inner and outer face thereof. The nut M is then engaged with the threaded portion 65 L of the post to clamp the latter firmly to the hood. Thus the externally projecting terminals are permanently attached to the heating element, and in such a manner as to permit of quickly removing the hood, which is 70 secured to the base A by a single bolt R.

The units E are clamped to the base by suitable means, such as the cap screws S, and cap plates T are preferably placed over each unit to hold it in position and also to form 75 the heat equalizer.

In use the terminal posts I may be engaged with a socket fitting U, which is attached to the cord or flexible connection V.

What I claim as my invention is:

1. An electrically-heated sad iron comprising a base section and a removable hood section, a heating element secured to said base section within said hood and a terminal 80 permanently attached to said heating element and projecting outward through an aperture in said hood.

2. An electrically-heated sad iron comprising a base section, a hood section, a heating element secured to said base section within said hood, a terminal permanently attached to said heating element projecting 90 outward through an aperture in said hood and insulated clamping means for mechanically attaching said terminal to the hood.

3. An electrically-heated sad iron comprising a base section, a hood section, a heating element attached to said base within said hood and a terminal permanently attached to said heating element having a flexible 100 and resilient portion and a rigid portion projecting outward through an aperture in said hood, means for clamping said rigid portion to said hood and means for insulating the terminal from the hood.

4. An electrically-heated sad iron comprising a pointed base section, a plurality of electrical heating units clamped to said base, one of said units being arranged centrally and extending adjacent to the forward point of 110 said base and a pair of units being arranged respectively upon opposite sides of said base

and overlapping said central unit, terminal connections to the opposite members of said pair and bridge connections between said central unit and the unit on opposite sides thereof.

5. An electrically-heated sad iron comprising a base section, a heating element clamped to said base, a hood section detachable from said base for inclosing said element, terminal connections permanently attached to said element and projecting outward through apertures in said hood, means for securing said hood to said base and insulated clamping means for securing said terminals to said hood.

10 6. An electrically-heated sad iron comprising a base section and a removable hood section, a heating element secured to said base section within said hood, terminals permanently connected to said base and passing outward through apertures in said hood, an

insulated clamp for rigidly attaching said terminals to said hood, and a socket fitting for engaging the projecting portion of said terminals.

25 7. An electrically-heated sad iron comprising a base section, a removable hood section having apertures therein, means for securing said hood to said base, a plurality of heating elements attached to said base within said hood, terminals permanently attached to said heating elements and projecting out through the apertures in the hood, and insulated clamping means for securing said terminals to said hood.

30 In testimony whereof I affix my signature in presence of two witnesses.

FRANK KUHN.
